TUBE-COILING MACHINE

Application filed October 20, 1928. Serial No. 313,683.

The present invention relates to a coiling apparatus designed broadly for forming flat coils of a flexible material as the same is fed or delivered thereto. It relates more particularly to an apparatus for coiling flexible tubular bodies such as hose as the same is manufactured, treated or finished.

The principal object of the invention is to provide an apparatus automatic in its operation for coiling the flexible body, and in which the material feeding or laying mechanism automatically reverses when the periphery or center of the coil is reached, thereby causing the formation of superimposed coiled layers of flexible material, all of which are substantially uniform. Another object of the invention is to provide an automatic apparatus for the purpose described, and wherein the speed of travel of the feeding apparatus or conveyer frame radially of the coiling table is controlled by the speed or rotation of the coiling table.

With the above mentioned and other objects in view, the invention consists in the novel construction and combination of parts hereinafter described, illustrated in the accompanying drawings, and set forth in the claims hereto appended, it being understood that various changes in the form, proportion, size and minor details of construction within the scope of the claims may be resorted to without departing from the spirit or sacrificing any of the advantages of the invention.

To more fully comprehend the invention, reference is directed to the accompanying drawings, wherein:

Fig. 1 is a view in plan of the preferred embodiment of our invention with the coiling table illustrated in dotted lines.

Fig. 2 is a view in end elevation, and

Fig. 3 is a transverse section on line 3—3 of Fig. 1.

In the several views, wherein like characters of reference indicate corresponding parts, 1 is a supporting base or frame illustrated as of angle iron construction, and mounted on the member 2 thereof is a bearing casting 3. The bearing casting 3 is provided with a vertical bore 4 into which ex-

tends and within which is rotatably mounted a table supporting spindle 5 mounting a relatively flat circular table 6, which is horizontally disposed. A shaft 7 extends laterally from the casting 3 radially beneath the table 6, the same being rotatable in bearings 8 and longitudinally slotted at 9. On its end the shaft carries a power pulley 10, and it also mounts for rotation with it a table rotating wheel 11 slidable longitudinally of the shaft through the medium of a key 11' carried by the hub of the wheel and projecting into the slot 9. The wheel on its periphery mounts a friction surface 12 which has frictional driving contact with the under surface of the table and causes the rotation of the table on the rotation of the shaft.

Disposed parallel with shaft 7 is a shaft 13 rotatable at its ends in bearings and connected through intermeshing gears 14 with the hub 15 of a bevel gear 16 rotatable on spindle 16'. The gear 16 intermeshes with the bevel gear 17 on the under side of the table 6 enabling the rotation of table 6 by wheel 11 to rotate shaft 13. A flexible pad of yieldable material 17' is positioned between the bevel gear 17 and the under side of the table 6.

The shaft 13 is provided for a portion of its length with a reverse screw thread 18 constituting a feed for causing the movement of a feed mechanism radially over the table to deliver the material thereto to be coiled thereon on the rotation of the table. Slidable on the shaft 13 is a sleeve 19 carrying spaced arms 20 embracing shaft 7, one on either side of the friction drive table rotating wheel 11. The sleeve 19 carries a pin 21 projecting into the thread 18, whereby the sleeve is caused to reciprocate longitudinally of the shaft 13 during its rotation and move the table frictional drive wheel 11 longitudinally of its shaft and radially beneath the table.

The frame 22 substantially U-shaped in side elevation extends upwardly from the sleeve 19 with its upper end overlying the table, as in Fig. 2. The upper end of the frame supports the discharge end of a conveyer 23 of any suitable type, and from the

end of which is discharged at a uniform speed the flexible material 24 to be coiled on the table 6.

It will thus be observed that the material 24 to be coiled is delivered at a uniform and constant speed on to the table 6, and as it passes between the guide fingers 24', its point of delivery on to the table gradually moves from the center outwardly to the 10 periphery of the table forming one flat coil, and then reverses and travels inwardly forming another flat coil superimposed on the coil below. This operation continues automatically until the desired number of coil 15 layers are provided. With the feeding or the delivery of the material on to the table being constant, it will be apparent that the coils will be more rapidly formed near the center of the table than adjacent its periphery, and 20 to compensate for this condition it will be observed that by driving the shaft 13 through gears receiving their power from the operation of the table, the sleeve 19 travels at a greater speed longitudinally of its shaft when 25 near the shaft's inner end than when adjacent its outer end.

Suitable idler rollers 25 may be provided for forming with the wheel 11 a three point suspension for the periphery of the table.

30 To facilitate the ready removal of the coils of material from the table, it is understood that, if desired, suitable frame or platform devices may be removably mounted on the surface of the table.

35 We claim:

1. A coiling apparatus comprising a horizontally rotatable table in fixed placement, drive means frictionally engaging with said table and adapted to radially reciprocate relative thereto in a closed path at one side of the axis of rotation, a frame having keyed engagement with a rotatable reverse screw thread, said frame having engagement with said drive means so as to reciprocate in unison therewith and having a portion overlying said table, a conveyor mounted on said frame having a discharge end positioned in substantial vertical alignment with the frictional contact of the drive means with said 40 table.

2. A coiling apparatus comprising a horizontally rotatable table in fixed placement, drive means frictionally engaging with said table and adapted to radially reciprocate 45 relative thereto in a closed path at one side of the axis of rotation, a frame having keyed engagement with a rotatable reverse screw thread, said frame having engagement with said drive means so as to reciprocate in unison therewith and having a portion overlying said table, a conveyor mounted on said frame having a discharge end, a guide for discharged material mounted on said frame adjacent the discharge end of the conveyor, 50 said discharge end and guide being positioned 55

in substantial vertical alignment with the frictional contact of the drive means with said table.

In testimony whereof, we have signed our names to this specification.

SAMUEL S. SHARER.
